METHOD OF MAKING PAPER ARTICLES

Kempton Clark, Little Compton, R. I., assignor to American Seal-Kap Corporation of Delaware, Wilmington, Del., a corporation of Delaware

Original application April 11, 1934, Serial No. 720,066. Divided and this application December 28, 1937, Serial No. 182,033

1 Claim. (Cl. 18—56)

This invention relates to a method of making paper articles and more particularly to those intended to contact with foods. One example of such an article is a milk bottle cap or closure, and while it should be understood that the invention is not to be restricted in its broadest aspects to closures for milk bottles, the invention will be hereinafter more particularly described with relation to such use.

10 This application is a division of my application Ser. No. 720,066, filed April 11, 1934 for Paper article.

In many cases it is desirable to use colors in connection with such articles, as for the purpose of producing ornamental effects or for distinguishing between grades or types of milk. For example, one color may be used in connection with bottles containing cream, another color may be used in connection with bottles containing certified milk, another color for bottles containing buttermilk, and so on, through the various grades and qualities for which such designations may be desired. Likewise it may be desired that certain colors be used exclusively by certain dairies, particularly in any given district, in order that the products of the various dairies may be readily distinguished. Likewise in some localities the use of colored lettering is employed on the bottles themselves and it then may be desirable 20 to employ sealing caps presenting the same color as the letters on the bottles.

In most cases, however, it is undesirable that the food products themselves should come into contact with colored paper material, not only because with the use of certain coloring materials there might actually be some chance of contamination of the food product, or some undesired effect on the coloring material itself through contact with such product, but also because the public has been generally educated up to the point where there is a real demand for closure members which present an appearance of extreme purity and cleanliness where the food products are brought into contact therewith.

45 According to this invention, therefore, the caps are formed of a paper material which presents exteriorly the desired color but which on the opposite face presents material entirely free from coloring material. In order to accomplish this purpose the paper used is preferably of multi-ply stock, one face portion only being colored, the other face portion being free from coloring matter. The use of multi-ply paper permits the application of coloring matter to the stock of one or more of the plies before the plies are brought

together to form the completed paper, the several layers of material being brought together while they are in a wet and more or less plastic condition so that they interfeet with each other in a manner well known in manufacture of multi-ply paper.

It is, of course, important that the manufacturing processes in making the caps be so carried out that the facing of the paper stock which contains the color forms the outside face of the cap, and in order to insure this and to insure ready handling of the paper in its various stages of formation, certain methods of handling the paper have been found highly desirable as will later more fully appear.

15 For a more complete understanding of this invention, reference may be had to the accompanying drawing in which

Figure 1 is a diagrammatic side elevation of a multiple cylinder paper machine arranged for sheeting a paper in accordance with this invention.

Figure 2 is a fragmentary perspective of a multi-ply paper such as is produced by the mechanism shown in Figure 1 and which forms the basic material from which the caps are made.

Figure 3 is a diagrammatic view illustrating the cutting of the paper into blanks from which the caps are made and certain subsequent treatments to which these blanks may be subjected before forming them into caps.

Figure 4 is a fragmentary perspective showing a blank as in the condition subsequent to treatment by the apparatus of Figure 3.

Figure 5 is a diagrammatic representation of a manner of supporting and feeding the several blanks to the cap-forming dies.

Figure 6 is a perspective partly broken away of one form of completed cap.

Referring first to Figure 1, at 1, 2 and 3 are shown the several vats containing the paper stock from which the several plies of the paper are to be made. As shown, the vat 1 contains a stock which is colored by any suitable means, such, for example, as a pigment or a dye of the desired color. A more detailed discussion of the desirable characteristics of such coloring will be given later. The vats 2 and 3 are shown as containing uncolored stock which should be of such a nature that it contains no substances such as would be deleterious to the food product with which it is to contact. While three separate vats are illustrated by which a three-ply paper may be made, it should, of course, be understood that any desired number might be used. Further reference

to the desirability of any particular number of plies will later appear.

As shown, each one of the vats contains a pick-up cylinder or cylinder mold such as 4, 5 and 6, which picks up the stock from its respective vat and applies it to the under face of the usual blanket 1 which passes successively over and in contact with the molds 4, 5, and 6, being pressed thereagainst by suitable couch rolls 8, 9 and 10. The blanket then passes about a suction roll or other similar device as at 11 for the purpose of more completely removing the water from the stock and from which it passes over suitable supporting rolls 12, between the press rolls 13 and 14, the blanket returning around the roll 14 while the sheeted paper passes to the drier indicated conventionally at 15 from which it may be fed off to any suitable device, for example, a winder shown at 16.

The paper thus produced is illustrated in Figure 2 and comprises a colored lamination 20 and two uncolored laminations 21 and 22. Paper for use as milk bottle caps and which is subjected to a severe molding action when being died to form should be of a somewhat open and porous nature so that it can be readily impregnated by materials such as water and waterproofing or resistant materials such as wax, which not only facilitate the molding operation, but also render the caps when completed substantially waterproof.

It has been found in practice that it is most advantageous to have substantially only one-third of the total paper by weight or thickness colored. If there is less than this, the uncolored portion of the paper will tend to show through on the colored side, particularly where the paper is subjected to substantial forming operations when being molded, which tends to produce undesirable surface abrasions or local thinning free from color. If the amount of colored stock is more than one half of the total, there is a tendency for the color to show through the uncolored side, particularly after waxing, to such an extent that it will give the appearance of being present on that side of the article which is brought into direct contact with the milk, which also is undesirable. While the most satisfactory proportions of thickness of colored and uncolored stock is generally about 1 to 2, this may vary from, according to conditions, of, say, about 1 to 3 to 1 to 1, with the thickness of paper most suitable for molding into milk bottle caps.

As the paper is subjected to moistening, as well as the wax treatment, in order to facilitate the molding operation, it is, of course, necessary that the color should be thoroughly set so as to prevent bleeding of coloring matter into the uncolored portion or plies of the paper. Furthermore, as the articles when in use may become moistened by contact with the milk, any such bleeding or flow of the color might have a very deleterious effect and even might escape into the milk. The sealed milk bottles are also subjected to other conditions of great severity with relation to coloring material in the caps, such, for example, as the icing operations which not only subject the caps to the action of cold water, but also to abrasive actions of the ice. Two classes of coloring material are the most satisfactory, these being pigments, and dyes of the type known as direct dyes. Such dyes have a great affinity for sulphite pulp such as is most suitable as a basic stock material for bottle caps, and they may be thoroughly set by the use of a hot salt solution.

Most dyes used in papermaking are set by alum, but for paper which is to be impregnated with waxes or the like, the use of alum is sometimes disadvantageous, and unless a size is employed with alum, the retention of the color and the setting effect by the alum is less efficient. Where pigments are employed the use of a small amount of size helps to retain the pigment, but of course this detracts to some extent, at least, from the open and porous character of the paper and the ease with which it may be impregnated with the wax. With the use of direct dyes the salt which is used in setting them is easily washed out and has no bad effect on the paper stock and such dyes do not bleed into the wax as is the case with many dyes commonly used in papermaking. Not only would such bleeding into the wax be disadvantageous in that the color might spread through the uncolored portions of the paper, but it might also contaminate the wax in the treating tank through which the blanks pass and thus pass into subsequently treated blanks in those portions where color is not desired.

In order to make a paper satisfactory for the molding operations, it is also advantageous to hold the degree of saturating qualities and the tensile strengths in directions longitudinally and crosswise of the paper within proper limits, these limits depending somewhat on the severity of the stresses produced by the molding operations, which are in turn dependent on the amount of deformation which the paper must undergo during such molding.

The paper thus prepared may then be subjected to treatment both to condition it for resistance to moisture and for the molding operation to which it must be subjected in forming it into the caps. In Figure 3 is shown diagrammatically an apparatus by which the paper is cut into blanks and impregnated with the desired waterproofing agents and otherwise conditioned for the molding operation. As shown in this figure, the paper is led from a suitable supply source, herein shown as the roll 30, through a punching mechanism indicated at 31, by which blanks 25 of the proper size are severed from the sheet material, the waste portions of the paper being then removed as by being wound up into a roll 32 while the blanks 25 themselves are passed, as by the conveyor 33 to the impregnating tank 34. Sometime previous to being incorporated with the water-proofing materials, it is preferable to subject either the blanks or the paper to a moistening action which swells the fibres of the paper and softens it so that it may be more easily formed between molding dies, and this moistening is done preferably prior to the treatment for moisture resistance, since it may aid in the impregnating operation. Agents which may add to the strength or hardness of the completed caps or add other desirable qualities may be added to the treating water, if desired. The blanks in moist condition are shown, therefore, as being fed in between confronting faces of reticulated feeding belts 35 and 36, the reticulations permitting the water-resistant material, such as a suitable wax or mixture of waxes in molten condition, to find ready access to opposite faces of the blanks. By causing the treating waxes to be maintained at a temperature somewhat above the boiling point of the moisture in the blanks, a portion of this moisture is vaporized and passes off from the blanks so that as the blanks pass out from the wax tank with a surface coating of molten wax thereon, subsequent

chilling of the blanks and condensation of the moisture vapor therein, acts to draw in the wax from the blank surfaces, resulting in a more thorough penetration of the wax into the interstices and perhaps even into the fibres of the paper. The blanks after removal from the tank are permitted to cool and are then deposited in any suitable receptacles. It is then preferable to permit the moistened and saturated blanks to stand for a time in order that they may become "conditioned" or "tempered" and uniformly sufficiently plastic to be most suitable for the molding operations. For this purpose they may be kept in closed containers for a few hours.

When properly conditioned they may be subjected to the forming action between suitable dies as has been illustrated diagrammatically in Figure 5. As therein shown the blanks 25 are fed out one at a time from the lower end of a suitable containing tube 40 by means of a feed plate, such as 41, which may be reciprocated across the open lower end of the tube 40 by any suitable means, so that they may be delivered one at a time to any suitable conveying means, as at 42, and brought in between the upper and the lower cap-forming dies 43 and 44 by which they are formed into the finished caps, one form of which may be as illustrated in Figure 6 at 45. For example, the cap thus formed may have a central disk-shaped portion 46 which bridges the neck of the milk bottle, this portion 46 having an upstanding wall 47 at its margin for engagement with the inner face of a milk bottle above the usual disk-receiving ledge therein, an outwardly turned portion 48 covering over the pouring lip of the bottle, and a skirt 49 depending therefrom to engage the outer face of the pouring lip. The entire outer face of the cap presents the desired color while the entire inner face of the cap is of uncolored stock so that no colored stock is presented where it may contact with the milk in the bottle.

In connection with the feeding of the cap blanks from the container 40 so that they may be delivered as desired to the forming dies, it is important that the blanks should be so positioned relative to the feed plate 41 that at each reciprocation it may engage the lowest blank in the stack and remove it from the tube 40. There is a tendency in making blanks of a suitable thickness for formation into bottle caps for the blanks to "dish" through unequal rates of drying at opposite face portions thereof, or from other causes. Should such a slightly dished blank be presented with its convex face downward, this may cause difficulty in the feeding action by reason of the feeding edge of the plate 41 passing in under the edge of the blank, and it is important, therefore, that the blanks be presented so that if they are not exactly flat, their convexed faces are positioned upwardly. This will result in the outer edge of the blanks where the feed plate enters being engaged by the feeding edge of this plate so that the blanks will be removed successively from the bottom of the stack as desired. It will be noted, however, that the blanks must be presented to the forming dies right side up so that the colored face shall always appear on the outside rather than the inside of the cap, and it is therefore necessary, to insure proper feeding with such a mechanism, that provision be made so that the convex face of the blank shall always bear the same relation to the colored and uncolored faces. There are various ways of insuring this. For example, the

characters of the paper stock in the stock vats of the paper machine may be so controlled that the colored stock when sheeted and processed shall be more extended in the conditioned blank than the stock forming the remainder of the blank. This may be accomplished either through controlling the relative shrinkages of the two types of stock in the formation and drying of the paper, or through controlling the relative amounts to which these surface portions will be expanded by the saturating process, or through combinations of both. For example, this may be done by controlling the relative freeness or slowness of the colored and uncolored stock, as, by controlling the amount of beating to which the stock is subjected before it is employed in papermaking. Thus, if the uncolored stock is slower than the colored stock, the uncolored side of the paper tends to take up less water than the colored side. It expands less and therefore is on the concave side of the paper. Another factor which may be of use is the rate of cooling of the blanks on the two sides after they leave the saturating tank. With the uncolored side up, the colored side being against the face of the conveyor, the uncolored side cools the more rapidly and assists in cupping the blanks in the proper direction. This is illustrated in Figure 3 where the direction of cupping is changed as the blanks cool on the conveyor 31. There is also a further advantage from maintaining the uncolored stock slower than the colored stock in that the uncolored side of the paper is less porous and therefore takes up less of the wax from the saturating tank and is therefore less transparent, so that the probability of the color from the colored side showing through is reduced.

It is also important, particularly from the standpoint of color and uniformity of color, that the completed blanks be quite accurate in thickness as the thickness of the blanks determines the action of the parts of the die thereon which are relatively spaced by predetermined dimensions. The amount of moisture and the amount of saturating material, as also the amount of the paper stock, is thus of importance since all these factors determine the thickness of the blank when it reaches the forming dies. If the blank is not thick enough the color of the blank itself will show up in the completed article. Where the blank is highly compressed during the forming operations, the color effect is deepened and where the compression is produced through a wiping action of the dies thereon, a glossy deeply colored finish is produced, different from that of the colored face of the blank before being molded. By suitable disposition of the excess stock which must be compressed in the molding operation ornamental variations in shading may be produced. For example, areas of deeper color 50 separated by areas of lighter color in pattern formation as indicated in Figure 6 may be produced, producing a pleasing ornamental effect.

From the foregoing description of a preferred construction and a method by which it may be made, it should be understood by those skilled in the art that various changes and modifications might be made without departing from the spirit or scope of this invention as defined by the appended claim.

I claim:

The method of making a severely molded paper article which comprises forming a laminated paper blank with the laminations at opposite surfaces of the blank having different absorption 75

characteristics for moisture and wax, moistening the blank, passing the same through a wax bath at a temperature and for a period of time to vaporize the moisture and draw a predetermined amount of the wax into the fibers thereof, allowing the same to set for a time to render the blank plastic for molding while the different absorption characteristics of the laminations causes the blank to cup with the lamination having the higher absorption characteristics on the convex side, and forming the cupped blank into an article having a substantially flat, disc-like

central portion and an inverted, generally U-shaped marginal portion forming an upstanding marginal rim with the convex side of the blank forming the convex side of said marginal rim, the amount of wax absorbed being sufficient to permit said forming operation to take place without cracking or abrading the paper to an extent that would cause either lamination to show through the other lamination and be visible from the opposite surface of the article.

KEMPTON CLARK.
